(57) **CLAIM**

The ornamental design for a razor handle, as shown and described.

DESCRIPTION

FIG. 1 is a perspective view of a razor handle showing our new design;

FIG. 2 is a front view thereof;

FIG. 3 is a back view thereof;

FIG. 4 is a right side view thereof;

FIG. 5 is a left side view thereof;

FIG. 6 is a top view thereof;

FIG. 7 is a bottom view thereof;

FIG. 8 is a rear perspective view thereof; and,

FIG. 9 is an alternate perspective view.

In the drawings, the evenly-spaced broken lines illustrate portions of the razor handle and form no part of the claimed design. The dash-dot broken lines illustrate a boundary to the claim and form no part thereof.
